Mounting for Window Ventilators

Filed June 14, 1946

UNITED STATES PATENT OFFICE

2,493,123

MOUNTING FOR WINDOW VENTILATORS

Bryant Essick, Los Angeles, Calif., assignor to
 Essick Manufacturing Company, Los Angeles,
 Calif., a corporation of California.

Application June 14, 1946, Serial No. 676,731

4 Claims. (Cl. 98—99.6)

1

This invention has to do with air handling apparatus and is more specifically concerned with a mounting for a window ventilator applicable to an ordinary window such as occurs in the average dwelling house. It is a general object of the present invention to provide a simple, neat and effective structure readily applicable to an ordinary window.

Most dwelling houses are constructed with windows of the type ordinarily known as double hung windows, this type of window being characterized by a window frame with two spaced vertical guideways each of which carries a sash in which there is a pane of glass. A sill is provided at the bottom of the case immediately forward of the innermost guideway. My present invention is primarily concerned with air handling apparatus applicable to a window of the type just referred to and it is a general object of the invention to provide a unit that can be readily applied to such a window so that it is mounted securely, is slight in appearance, and that does not mar or mutilate any part of the window construction, either the frame or the window sash.

A further object of my present invention is to provide a very simple inexpensive construction whereby a box-like body carrying a fan or any air handling apparatus is mounted in a window to rest on the sill and to have a lip that bears forward on the sill and a lip that bears rearward on the glass carrying window sash to the end that the body is firmly supported and is maintained tightly in position, mainly by virtue of its own weight, while the major portion of the body projects from the sash at the exterior of the structure in which the window occurs.

Another object of my invention is to provide a simple, improved construction whereby the unit that I have provided can be readily accommodated to windows of various widths.

The various objects and features of my invention will be fully understood from the following detailed description of a typical preferred form and application of the invention, throughout which description reference is made to the accompanying drawings, in which:

Fig. 1 is a front elevation of the structure provided by my invention showing it applied to a typical double hung window. Fig. 2 is an enlarged vertical sectional view of the window structure showing the unit that I have provided in place therein and showing parts broken away to appear in section. Fig. 3 is a plan view of the unit that I have provided showing it in place in the window.

2

My present invention is primarily concerned with a unit or device applicable to a double hung window and in the drawings I have shown such a window structure. In accordance with common construction the window involves, generally, a frame A and a pair of glass carrying sashes B carried by the frame. The frame involves, generally, vertical sides 10 and a bottom or ledge 12. The sides 10 have spaced opposed panels or guideways 14 that carry the sashes B and at the bottom of the frame there is a sill 13 that projects above the ledge 12 and projects a suitable distance forward from the innermost guideway. The window sash B is a simple rectangular frame, usually formed of wood carrying a pane of glass 15. In the drawings I have shown only the lower portion of the innermost sash B since my construction is designed to cooperate with this particular part of the window. The inner sash B of the window, as shown in the drawings, includes a lower cross member 16 and vertical side members 17 which slide in the innermost guideway 14.

The structure that I have provided includes, generally, a body C which is a box-like structure and which is provided or formed with few simple parts to facilitate its application to a window constructed as above described. The body is generally a casing or housing carrying or accommodating air handling or treating equipment. For instance, it may house a motor driven fan F or it may include or carry filter pads or other equipment, as desired. So far as my present invention is concerned it will suffice to point out that the body has a top 20, a bottom 21, sides 22 and a back 23. The body further includes a front panel 24 which is of special construction as provided by my invention. In the particular case illustrated the sides 22 and back 23 are of louvered formation while the top, bottom, and sides have inwardly turned flanges 26 to which the front panel may be attached so that the body forms a complete, assembled unit, box-like in character. It is to be understood that in practice any suitable means may be used to join the various parts of the body and the elements of the body that I have referred to can be either integrally joined or made separable as circumstances require.

In accordance with my invention the front panel 24 faces into the room or faces inwardly when the structure is in position in a window, and therefore it is finished part, neat and slight in appearance. The front panel in the case illustrated has a central opening 30 to pass air and this opening is provided in a raised section

31. The panel 24 is also shown as provided with embossed parts or ribs 32 which extend horizontally and enhance the appearance of the structure. I provide the lower edge portion of the front 24 with a rearwardly or outwardly projecting flange 35 which extends horizontally and is such as to rest upon the window sill 13. The projecting edge portion of the flange 35 is provided with a depending lip 36 which extends down behind the sill 13. The top edge portion of the front 24 is provided with a rearwardly or outwardly projecting flange 37 of substantially the same extent as the flange 35 which flange 37 terminates in an upwardly projecting lip 38 which, when the device is in use, bears against the front side 39 of the sash member 16.

At each vertical edge of the front 24 there is a rearwardly or outwardly extending flange 40 similar to the flanges 35 and 37 and the flanges 40 preferably terminate in laterally projecting ears 41.

I apply the structure that I have thus provided to a common or typical double hung window construction of the type described by simply resting the flange 35 on the sill 13 so that the lip 36 engages behind or against the outer edge of the sill, and I lower the window sash B so that the sash member 16 closely approaches or bears on the top 20 of the body C while the lip 38 bears outwardly against the face 39 of member 16. With the parts in this position, as shown in Fig. 2, the body projects outwardly in the window opening and may extend a substantial distance out beyond the structure in which the window occurs. The action of gravity on the body causes it to tend to turn in a manner to keep the lip 36 tight against the sill 13 while the lip 38 is maintained tight against the sash member 16.

I may, in practice, make the body that I have described of a width to properly fit the particular window in which the device is to be used. However, ordinarily I make the body somewhat narrower than the window opening and provide filler plates 50 at each side of the body to extend from the body to the sides of the window frame. Each filler plate 50 may be a simple flat plate cut wide enough to occupy the space between the body C and the side of the window frame, it being preferred to proportion each filler plate so that it engages behind an ear 41 and extends into a channel 14 in the frame and to make it long enough so that it coincides in vertical extent with the front 24 of the body. In practice I may make the filler plates 50 simple flat plates and depend on wedging them or pressing them tightly into position. However, I prefer to make them secure, as by turning a flange 60 on each plate 50 to seat in the bottom of the innermost channel 14 of the frame and the flanges 60 may be made secure in the case by nails 61 or other fastening means.

In carrying out my invention I prefer to form the front 24, the several flanges in connection therewith, the lips and ears above described, as a single integral or continuous part, for instance, I prefer to make these elements as a single stamping, as shown throughout the drawings.

Having described only a typical preferred form and application of my invention, I do not wish to be limited or restricted to the specific details herein set forth, but wish to reserve to myself any variations or modifications that may appear to those skilled in the art and fall within the scope of the following claims.

Having described my invention, I claim:

1. A unit applicable to a window having a frame with channeled sides carrying inner and outer sashes and a sill at the bottom including, a box-shaped body having a top, bottom and side walls defining a front opening and having a substantially flat vertical sheet metal front panel closing the said front opening of the body and having an air passing opening therein substantially smaller than the said front opening, the front panel having its lower edge portion turned to extend outwardly in the frame forming a first horizontal flange immediately adjacent the lower edge of the vertical front panel for resting on the sill with the front panel in a plane immediately forward of the inner side of the inner sash, the projecting edge portion of the said first flange extending down forming a lip for engagement against the edge of the sill, the upper edge portion of the front panel being turned to extend outwardly in the frame forming a second flange the projecting edge portion of which extends up forming a lip for bearing engagement against the side of the inner sash, the said flanges and lips being integral with the sheet forming the front panel.

2. A unit applicable to a window having a frame with channeled sides carrying inner and outer sashes and a sill at the bottom including, a box-shaped body having a top, bottom and side walls defining a front opening and having a substantially flat vertical sheet metal front panel closing the said front opening of the body and having an air passing opening therein substantially smaller than the said front opening, the front panel having its lower edge portion turned to extend outwardly in the frame forming a first horizontal flange immediately adjacent the lower edge of the vertical front panel for resting on the sill with the front panel in a plane immediately forward of the inner side of the inner sash, the projecting edge portion of the said first flange extending down forming a lip for engagement against the edge of the sill, the upper edge portion of the front panel being turned to extend outwardly in the frame forming a second flange the projecting edge portion of which extends up forming a lip for bearing engagement against the inner side of the inner sash, the front panel having side flanges at its vertical edges extending outwardly in the frame and having lips occurring in substantially the same planes as the lips of the said first and second flanges, and fillers engaged behind the lips of the side flanges and extending therefrom to the channel of the frame carrying the inner sash, all of the said flanges and lips being integral with the sheet forming the front panel.

3. A unit applicable to a window having a frame with channeled sides carrying inner and outer sashes and a sill at the bottom including, a box-shaped body having a top, bottom and side walls defining a front opening and having a substantially flat vertical sheet metal front panel closing the said front opening of the body and having an air passing opening therein substantially smaller than the said front opening, the front panel having its lower edge portion turned to extend outwardly in the frame forming a first horizontal flange immediately adjacent the lower edge of the vertical front panel for resting on the sill with the front panel in a plane immediately forward of the inner side of the inner sash, the projecting edge portion of the said first flange extending down forming a lip for engagement

against the edge of the sill, the upper edge portion of the front panel being turned to extend outwardly in the frame forming a second flange the projecting edge portion of which extends up forming a lip for bearing engagement against the side of the inner sash, the said flanges and lips being integral with the sheet forming the front panel, the top, bottom and side walls of the body being formed of sheet metal and each having an inwardly projecting part integral therewith and engaged behind the front panel, said parts being attached to the marginal portions of the front panel reinforcing the front panel and serving to connect the front panel with the other elements of the body.

4. A unit applicable to a window having a frame with channeled sides carrying inner and outer sashes and a sill at the bottom including, a box-shaped body having a top, bottom and side walls defining a front opening and having a substantially flat vertical sheet metal front panel closing the said front opening of the body and having an air passing opening therein substantially smaller than the said front opening, the front panel having its lower edge portion turned to extend outwardly in the frame forming a first horizontal flange immediately adjacent the lower edge of the vertical front panel for resting on the sill with the front panel in a plane immediately forward of the inner side of the inner sash, the projecting edge portion of the said first flange extending down forming a lip for engagement against the edge of the sill, the upper edge portion of the front panel being turned to extend outwardly in the frame forming a second flange

20

25

30

35

the projecting edge portion of which extends up forming a lip for bearing engagement against the inner side of the inner sash, the front panel having side flanges at its vertical edges extending outwardly in the frame and having lips occurring in substantially the same planes as the lips of the said first and second flanges, and fillers engaged behind the lips of the side flanges and extending therefrom to the channel of the frame carrying the inner sash, all of the said flanges and lips being integral with the sheet forming the front panel, the top, bottom and side walls of the body being formed of sheet metal and each having an inwardly projecting part integral therewith and engaged behind the front panel, said parts being attached to the marginal portions of the front panel reinforcing the front panel and serving to connect the front panel with the other elements of the body.

BRYANT ESSICK.
